UNITED STATES PATENT OFFICE

DAVID W. R. MORGAN, OF SWARTHMORE, PENNSYLVANIA, ASSIGNOR TO WESTINGHOUSE ELECTRIC & MANUFACTURING COMPANY, A CORPORATION OF PENNSYLVANIA

CONDENSER

Application filed February 11, 1927. Serial No. 167,510.

My invention relates to condensers for steam power plants, and it has for an object to provide apparatus of the character designated which shall deliver non-condensable fluids to the non-condensable fluid withdrawal means at an extremely low temperature and specific volume and which shall, at the same time, deliver to the hotwell condensate having a temperature closely approximating that of the exhaust steam. It has for its further object to provide a condenser wherein all of the tubes shall be so disposed as to be highly active in transferring heat and at the same time offer a minimum amount of resistance to the passage of the condensable and non-condensable fluids through the tube nest.

These and other objects, which will be made apparent through the further description of my invention, may be attained by the employment of the apparatus hereinafter set forth and illustrated in the accompanying drawings; in which,

Fig. 1 is a view, in sectional elevation, of one form of condenser arranged in accordance with my invention;

Figs. 2 and 3 are sectional views taken on the lines II—II and III—III respectively of Fig. 1;

Fig. 4 is a view in transverse sectional elevation; and,

Fig. 5 is a view, in longitudinal sectional elevation of other forms of condensers arranged in accordance with my invention.

Surface condensers of the so-called radial flow type commonly comprise a shell in which a circular nest of cooling tubes is eccentrically disposed with respect to a semi-circular bottom of the condenser shell and through which cold water is circulated to maintain the tubes at a relatively low temperature. The fluid to be condensed, hereinafter for distinction and brevity called steam, is usually received at the upper portion of the shell and flows through the nest of cooling tubes from the steam passages which substantially surround the tube nest, the condensate being extracted at a point adjacent the bottom of the shell. Air and non-condensable gases, which accumulate in the condenser, are usually extracted

through an air offtake, the inlet of which is disposed well within the nest of tubes, thereby causing a flow of the steam radially through the cooling tube nest toward the inlet of the air offtake member. Condensers of this type possess the distinct advantage of providing a heat transmitting surface of high efficiency by reason of the large entrance area presented to the steam entering the tube nest and further because of the uniformly short path of travel over the cooling tubes to the air offtake. This arrangement also insures that there will be no appreciable variation in pressure between the steam inlet and the point of complete condensation. Condensers of this type have now come into extensive commercial use.

It has been found, however, that with condensers of the radial flow type, as well as with all other types of condensers, the outer tubes initially engaged by the exhaust steam are more active from a standpoint of heat transfer than the more remote tubes. It has therefore been proposed, in a copending application of J. H. Smith, Serial No. 141,221, filed October 12, 1926, entitled "Condensers" and assigned to the Westinghouse Electric & Manufacturing Company, to omit, in condensers of the radial flow type, the tubes in the central portion of the tube nest or the tubes in the vicinity of the air offtake and to redistribute these tubes about the periphery of the tube nest, it being possible to do this with little increase in outside diameter of the tube nest and with little diminution in the activity of the prior outer zone of tubes. This arrangement provides a tube nest which is shaped in the form of a hollow cylinder having a centrally disposed core area in which no tubes are located and in this way there is provided a very efficient form of condenser so far as heat transfer is concerned.

Efficiency in the operation of condensers further demands that the energy expended in the withdrawal of the non-condensable fluids be reduced to a minimum, which result is most readily accomplished by reducing the volume of the fluids necessary to be handled by the air removal means prior to delivery thereto. It has heretofore been proposed to

partition off various portions of the tube nest for use as air cooling chambers and it has also been proposed to provide air cooling chambers located exteriorly and separate from the condenser shell. As a general rule, however, in such arrangements the cooling chamber occupies space which might otherwise have been used for condensing or other purposes.

I have, therefore, devised a condenser in which the tube nest is so arranged as to be of the radial flow type. All tubes have been omitted from the central core area of the nest in order that all of the tubes may be rendered highly effective in the transfer of heat. I further utilize this otherwise useless internal core space of the tube nest as an air and non-condensable gas cooling chamber, and, to this end, I provide a conduit having a relatively large flow area and occupying substantially the entire core space of the tube nest. This conduit is preferably of such proportions that it is capable of conveying all or a portion of the cooling water to the tube nest. In this way, a tremendous body of cooling water passes longitudinally through the center of the tube nest for the entire length of the condenser shell before its entry into the cooling tubes. Within this large centrally disposed conduit, I locate the air and non-condensable gas offtake so that it is subject to the cooling action of this large body of water which the conduit conveys. In other words, the air and non-condensable gases are subjected to the cooling action of all of the cooling water supplied to the condenser before they are withdrawn by the air removal apparatus and before this water has come in contact with the tube nest.

Intake manifolds for the air and noncondensable gas offtake are located circumferentially about the exterior of the large centrally disposed conduit and are spaced longitudinally of the condenser so that the air and noncondensable gases are withdrawn over an unusually large region and hence there is no such material segregation of the air and noncondensable gases at any one point in the condenser shell as will insulate or blanket any portion of the tube nest.

It will, therefore, be apparent that I have provided a condenser which embodies all three desirable, basic features in that it is of the radial flow type, has all of its tubes arranged in the form of a thin annular band so that every tube is highly active, and has a very effective air and non-condensable gas cooling chamber which is so located in the condenser as to occupy that portion of the condenser shell which is not readily adapted for condensing purposes.

Referring to the drawings for a more detailed description of my invention, I show a condenser shell 10 provided with an exhaust steam inlet 11 and a condensate outlet 12. Secured to the respective ends of the con-

denser shell are tube sheets 13 and 14 to which are connected suitable water boxes 15 and 16.

As shown in Fig. 2, a tube nest 17 is located within the shell. As is apparent from the drawing, the tube nest is preferably arranged in the form of a hollow cylinder, the tubes being supported in the tube sheets 13 and 14 in a manner well understood in the art. The tube nest is so located within the shell that the steam or fluid to be condensed can enter it at substantially any point about its periphery, although I may, if I so desire, arrange this steam delivery space so that it surrounds only a portion of the tube nest. I may also make the cooling medium conduit and the noncondensable gas conduit eccentric with respect to the tube nest. It is further apparent from Fig. 2 that the tube nest is so cored out that the tubes are all arranged in the form of a relatively thin annular band having a maximum entrance area and a minimum length of radial steam travel.

Located within the core space 18 of the tube nest is a conduit 19 which is preferably of such proportions that it is capable of conveying all or a substantial percentage of the cooling fluid required by the tube nest. The tube sheets 13 and 14 are preferably annular in shape and the conduit 19 is supported at its one end 20 upon the inner periphery of the tube sheet 13 while a stuffing box 20' is provided at the other end for permitting longitudinal movement of the conduit relative to the tube nest. The conduit 19 may be arranged in sections, as illustrated, to facilitate assembly of the condenser although this construction may be varied to suit the requirements. It will be apparent from the drawing that the conduit 19 serves to stay the condenser longitudinally.

As is customary with condensers of large capacity, a plurality of intermediate tube supporting plates 21 and 22 are provided dividing the condenser shell into, what may be termed, compartments 23, 24 and 25. Each of these compartments is provided with a circular air and non-condensable gas intake manifold 26 having a plurality of radially disposed inlets 27, the manifold being connected by two or more radially disposed conduits 28 to an air and non-condensable gas offtake main 29 located in the central portion of the conduit 19 and extending longitudinally with it. The air and non-condensable gas offtake main 29 is provided with a plurality of expansion joints 30. It is arranged to terminate in a wall of the water box 16, as at 31, where it may be connected to the air removal apparatus in a manner well understood in the art. The water box 15 is provided with an intake passage 32 arranged to connect directly with the entrant portion of the conduit 19 while water box 16 is cuspidated so as to radially convey the cooling water from the discharge portion of the conduit 19 to the en-

trant end of the tube nest with a minimum amount of resistance to flow. As shown in Fig. 3, the water box 15 has an annular passage surrounding the intake 32 and connecting with an outlet 33 for the discharge of the 5 cooling water leaving the tube nest.

From the foregoing description, the operation of my condenser will be apparent. Exhaust steam is admitted to the condenser shell through the inlet 11 and substantially surrounds the entire nest of tubes. Exhaust steam is drawn radially inward toward the circumferentially disposed inlets 27 of the several air and non-condensable gas intake 10 manifolds 26 and the steam is condensed in its 15 passage over the cooling tubes. As the tube nest is arranged in the form of a thin annular band it will be apparent that the distance of vapor travel is a minimum, that the spacing and distribution of the tubes is such that immediate and intimate contact of steam therewith is assured, and that the residual velocity energy of the steam is very little absorbed. In addition, because of the extremely 20 large circumference of each intake manifold as well as the large number of manifolds provided, the withdrawal of the air and non-condensable gases is not concentrated in any one locality but takes place over a very large 25 region and consequently there is substantially no blanketing or insulating of the tubes 30 in any locality.

Cooling water for the condenser is admitted through the intake 32 and passes directly 35 through the conduit 19 to the water box 16 wherein its direction of flow is reversed and it travels back through the tubes of the nest and leaves the condenser through the outlet 33. It is therefore apparent that an extraordinary or tremendous amount of 40 cooling water is available for reducing the temperature of the air and non-condensable gases passing through the offtake main 29 and leaving the condenser through the outlet 45 31. The locating of the conduit 19 within the tube nest, as pointed out heretofore, does not materially increase the size or proportions of the condenser because of the advantages obtained through omitting tubes in this 50 central core area. Condensate is withdrawn from the hotwell 12 in a manner well understood in the art.

The condenser disclosed is of the single-pass type, the cooling water being admitted 55 and discharged from the same water box. This arrangement is particularly desirable with installations wherein the condensers are located in a vertical position and where it is advantageous to both supply and discharge the water from the lower end. While I have 60 shown a condenser of the single-pass type, nevertheless, it is obvious that I may associate the conduit 19 with condensers of the multi-pass type without in any way departing from the spirit of my invention. In ad-

dition, it is also pointed out that, while I have illustrated a condenser of the radial-flow type, nevertheless, my invention is equally applicable to condensers of the down-flow type or to condensers of the partial radial and partial down-flow type. It is obvious 70 that the maximum cooling action can be obtained by circulating the cooling water first through the conduit and thence through the tube nest, although it is perfectly obvious 75 that if, for any reason, less intense cooling action is desired, the water may be readily circulated through the tube nest before its passage through the conduit 19. In other words, the direction of the flow of cooling 80 water can be readily reversed.

Referring now to Fig. 4, I show a condenser of the down-flow type which is provided with a shell 41 and a nest of cooling tubes 42, all arranged in a manner well understood in the 85 art. Extending longitudinally of the condenser shell 41 is a division plate 43 which defines with the shell 41 a relatively large cooling water passage or conduit 44 which corresponds with the conduit 19 of the condenser 90 shown in Fig. 1. Within the conduit 44 is located an air and non-condensable gas offtake main 45 provided with branch conduits, such as 46, which have their entrant portions 95 located in the lower portion of the condenser shell, as at 47.

In operation, the circulating water is first 100 conveyed through the conduit or passage 44 after which its flow is reversed and it returns through the nest of cooling tubes 42. Air and non-condensable gases are withdrawn from the condensing chamber through the branch conduit 46 and the air and non-condensable gas offtake 45 by any suitable form of air removal apparatus. It will therefore be apparent 105 that the air and non-condensable gases leaving the condenser through the offtake main 45 are subjected to the cooling action of the relatively large body of cooling water passing longitudinally through the conduit 110 44. This embodiment of my invention clearly demonstrates that my inventive idea is applicable to not only condensers of the radial-flow type but to condensers of the down-flow type as well.

In Fig. 5, I show still another embodiment 115 of my invention which is similar to that shown in Fig. 1, with the exception that the air and non-condensable gas offtake main 29 is not located inside of the centrally disposed 120 cooling water conduit 19 but, on the other hand, is arranged exteriorly of this conduit. This may be accomplished by providing a second conduit 51 concentrically without the conduit 19. The inner bore of the conduit 51 125 and the outer circumference of the conduit 19 define an annular air and non-condensable gas offtake main 52, a plurality of suitable inlet openings 53 being provided in the outer conduit 51. The air and non-condensable 130

gases leaving the offtake main 52 enter an annular passage 54 located in one of the water boxes. Connected to the annular passage 54 is an outlet passage 55 passing through the water box.

5 In operation, the cooling water passes longitudinally through the inner conduit 19 and thence through the tube nest. The air and non-condensable gases are drawn through the 10 openings 53 into the annular offtake main 52 and are withdrawn through the annular passage 54 and outlet passage 55 by suitable air removal apparatus. In passing through the 15 annular offtake main 52 and the annular passage 54, the air and non-condensable gases are very effectively cooled inasmuch as they are in constant contact with the large body of relatively low temperature cooling water passing through the water box 15 and the 20 conduit 19.

25 While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

30 What I claim is:

1. In a surface condenser having circulating water inlet and outlet connections located at a common end, the combination of a shell structure having a steam inlet and a condensate outlet, tube sheets fixedly secured at each end of the shell structure, a nest of cooling tubes extending between the tube sheets for conveying circulating water in a single direction through the shell structure, said shell structure forming a direct passage for steam between its inlet and the entire axial length of the tube nest, said tube nest connecting with one of the water connections, a single conduit embodied in and extending longitudinally of the shell structure, said conduit being connected at one end to the other of said water connections and communicating at its other end with all of the tubes of the nest and said conduit having a relatively larger flow-area than any of the tubes of the nest in order to convey adequate circulating water for all of the tubes of the nest.

2. In a surface condenser having circulating water inlet and outlet connections located at a common end, the combination of a shell structure having a steam inlet and condensate outlet, tube sheets fixedly secured at each end of the shell structure, a nest of cooling tubes extending between the tube sheets for conveying circulating water in a single direction longitudinally through the shell structure, said shell structure forming a di-

rect passage for steam between its inlet and the entire axial length of the tube nest and said tube nest connecting with one of the water connections, and a single conduit embodied in and extending longitudinally of the shell structure, said conduit being connected at one end to the other of said water connections and communicating at its other end with all of the tubes of the nest and said conduit having a relatively larger flow-area than any of the tubes of the nest in order to convey adequate circulating water for all of the tubes of the nest.

3. In a surface condenser having circulating water inlet and outlet connections located at a common end, the combination of a shell having a steam inlet and a condensate outlet, tube sheets fixedly secured at each end of the shell, a substantially cylindrical nest of tubes extending between the tube sheets and connecting with one of the water connections for conveying circulating water in a single direction longitudinally through the shell, said tube nest defining with the walls of the shell a steam delivery space surrounding a considerable portion of the tube nest and extending throughout the entire longitudinal length of the tube nest, and a single conduit extending longitudinally within the tube nest and connected at one end to the other of said water connections and communicating at its other end with all of the tubes of the nest, said conduit having a relatively larger flow-area than any of the tubes of the nest in order to convey adequate cooling water for all of the tubes of the nest.

4. In a condenser, the combination of a shell having a steam inlet and a condensate outlet, tube sheets fixedly secured at each end of the shell, a substantially cylindrical nest of tubes extending between the tube sheets and defining with the walls of the shell a steam delivery space surrounding a considerable portion of the tube nest and extending throughout the entire axial length of the tube nest, a conduit for supplying cooling water to the tube nest and extending longitudinally through the condenser shell and located in a central portion of the tube nest, and an air and non-condensable gas offtake disposed within the conduit and arranged to withdraw air and non-condensable gases from the inner portion of the tube nest.

5. In a condenser, the combination of a shell, a cooling tube dividing said shell into a condensing chamber and an air and non-condensable gas cooling chamber, a steam inlet and a condensate outlet provided in the shell and communicating with the condensing chamber, an air and non-condensable gas off-take connecting with the cooling chamber, a nest of condensing tubes disposed in the condensing chamber, said shell forming a direct passage for steam between its inlet and the entire longitudinal length

of the tube nest, and means for connecting one end of the tube nest to said cooling tube, said cooling tube having a relatively larger flow-area than any of the tubes of the nest in order to convey adequate cooling water for all of the tubes of the nest.

- 5 6. In a condenser, the combination of a shell having a steam inlet and a condensate outlet, tube sheets fixedly secured at each end of the shell, a nest of cooling tubes extending between the tube sheets, said shell forming a direct passage for steam between its inlet and the entire longitudinal length of the tube nest, a single conduit communicating with one end of the tube nest and extending longitudinally within the shell, said conduit having a relatively larger flow-area than any of the tubes of the nest in order to convey adequate cooling water for all of the tubes of the nest, and air and non-condensable gas off-take means disposed in heat exchanging relation with the conduit.
- 10 15 20

7. In a condenser, the combination of a shell having a steam inlet and a condensate outlet, tube sheets fixedly secured at each end of the shell, a nest of cooling tubes extending between the tube sheets, said shell forming a direct passage for steam between its inlet and the entire longitudinal length of the tube nest, a conduit communicating with one end of the tube nest and extending longitudinally within the shell to the other end of the tube nest, said conduit having a relatively larger flow-area than any of the tubes of the nest in order to convey adequate cooling water for all of the tubes of the nest, and air off-take means disposed within the conduit.

- 30 35 40 45 50
8. In a condenser, the combination of a shell structure having a steam inlet and a condensate outlet, tube sheets fixedly secured at each end of the shell structure, a nest of cooling tubes extending between the tube sheets, said shell structure forming a direct passage for steam between its inlet and the entire longitudinal length of the tube nest, a single conduit embodied in and extending longitudinally of the shell structure and communicating at one end with the tube nest, and air off-take means disposed in heat transfer relation with the conduit, said conduit having a relatively larger flow-area than any of the tubes of the nest in order to convey adequate cooling water for all of the tubes of the nest.

- 55 60 65
9. In a condenser, the combination of a shell having a steam inlet and a condensate outlet, tube sheets fixedly secured at each end of the shell, a nest of cooling tubes extending between the tube sheets, said shell forming a direct passage for steam between its inlet and the entire longitudinal length of the tube nest and each of the said tubes having a relatively small flow area, a conduit extending longitudinally within the shell and having a flow area not less than sixty times the flow area of the respective tubes, said conduit being

disposed in open communication with one end of the tube nest for conveying cooling fluid for all of the tubes and air and non-condensable gas offtake means disposed in heat exchanging relation with the conduit.

70

10. In a condenser, the combination of a shell having a steam inlet and a condensate outlet, tube sheets fixedly secured at each end of the shell, a nest of cooling tubes extending between the tube sheets, said shell forming a direct passage for steam between its inlet and the entire longitudinal length of the tube nest, said cooling tubes being so arranged within the shell as to define a longitudinally extending space, a single conduit in said space disposed in open communication with one end of the tube nest, said conduit having a relatively larger flow-area than any of the tubes of the nest in order to convey adequate cooling water for all of the tubes of the nest, and air and non-condensable gas offtake means arranged in heat transfer relation with the cooling fluid passing through the conduit.

80

11. In a condenser, the combination of a shell having a steam inlet and a condensate outlet, tube sheets fixedly secured at each end of the shell, a nest of cooling tubes extending between the tube sheets, said shell forming a direct passage for steam between its inlet and the entire longitudinal length of the tube nest and said cooling tubes being so arranged within the shell as to define a longitudinally extending hollow portion co-axial with respect to the tube nest, a single conduit occupying said hollow portion, said conduit being disposed in open communication with one end of the tube nest and said conduit having a relatively larger flow-area than any of the tubes of the nest in order to convey adequate cooling water for all of the tubes of the nest, and air and non-condensable gas offtake means located within the hollow portion in heat transfer relation with the cooling fluid passing through the conduit.

90

10. In a condenser, the combination of a shell having a steam inlet and a condensate outlet, tube sheets fixedly secured at each end of the shell, a nest of tubes extending between the tube sheets, said shell forming a direct passage for steam between its inlet and the entire longitudinal length of the tube nest, a water box associated with the inlet end of the tube nest, a water box associated with the discharge end of the tube nest, cooling water inlet and outlet means provided in the water box associated with the discharge end of the tube nest, a conduit for conveying the cooling water from the water box associated with the discharge end of the tube nest to the water box associated with the inlet end of the tube nest, said conduit having a relatively larger flow-area than any of the tubes of the nest in order to convey cooling water for all of the tubes of the nest, and air and non-condensable gas offtake means disposed in heat transfer relation with the cooling fluid passing through the conduit.

100

11. In a condenser, the combination of a shell having a steam inlet and a condensate outlet, tube sheets fixedly secured at each end of the shell, a nest of tubes extending between the tube sheets, said shell forming a direct passage for steam between its inlet and the entire longitudinal length of the tube nest, a water box associated with the inlet end of the tube nest, a water box associated with the discharge end of the tube nest, cooling water inlet and outlet means provided in the water box associated with the discharge end of the tube nest, a conduit for conveying the cooling water from the water box associated with the discharge end of the tube nest to the water box associated with the inlet end of the tube nest, said conduit having a relatively larger flow-area than any of the tubes of the nest in order to convey cooling water for all of the tubes of the nest, and air and non-condensable gas offtake means disposed in heat transfer relation with the cooling fluid passing through the conduit.

110

115

120

125

130

tact with the cooling water passing through the said conduit.

13. In a condenser, the combination of a shell having a steam inlet and a condensate outlet, tube sheets fixedly secured at each end of the shell, a substantially cylindrical nest of tubes extending between the tube sheets and defining with the shell a steam delivery space substantially surrounding the nest of tubes and extending throughout the entire axial length of the tube nest, said cylindrical nest of tubes having a relatively large core area, a single conduit occupying substantially the entire core space of the tube nest and disposed in open communication with one end of the tube nest, said conduit having a relatively larger flow-area than any of the tubes of the nest in order to convey adequate cooling water for all of the tubes of the nest, and an air and non-condensable gas offtake located in the path of the cooling water passing through the conduit.

14. In a condenser, the combination of a shell having a steam inlet and a condensate outlet, tube sheets fixedly secured at each end of the shell, a substantially hollow cylindrical nest of tubes extending between the tube sheets and defining with the walls of the shell a steam delivery space surrounding a considerable portion of the tube nest and extending throughout the entire longitudinal length of the tube nest, an air and non-condensable gas offtake extending through the hollow interior of the tube nest, means for conveying a relatively large quantity of cooling water about the air and non-condensable gas offtake, branch offtakes having their entrant portions located adjacent the inner periphery of the tube nest and connecting with the air and non-condensable gas offtake, and means for conveying cooling water to the tube nest.

15. In a condenser, the combination of a shell having a steam inlet and a condensate outlet, tube sheets fixedly secured at each end of the shell, a substantially hollow cylindrical nest of tubes extending between the tube sheets and defining with the walls of the shell a steam delivery space surrounding a considerable portion of the tube nest and extending throughout the entire longitudinal length of the tube nest, an air and non-condensable gas offtake extending through the hollow interior of the tube nest, means for admitting cooling water to the condenser, means for conveying said cooling water through the hollow interior of the tube nest and to the tubes of the nest, and radially extending branch conduits for connecting the inner periphery of the tube nest to the air and non-condensable gas offtake.

16. In a condenser, the combination of a shell having a steam inlet and a condensate outlet, tube sheets fixedly secured at each end of the shell, a cylindrical nest of tubes ex-

tending between the tube sheets and defining with the walls of the shell a steam delivery space surrounding a considerable portion of the tube nest, and extending throughout the entire longitudinal length of the tube nest, a conduit extending longitudinally through the shell for conveying cooling water for the tube nest, an air and non-condensable gas offtake extending within the conduit, and branch passages leading from the exterior of the conduit to the air and non-condensable gas offtake disposed within the conduit, whereby air and non-condensable gases are removed from the tube nest.

17. In a condenser, the combination of a shell having a steam inlet and a condensate outlet, tube sheets fixedly secured at each end of the shell, a substantially hollow cylindrical nest of tubes extending between the tube sheets and defining with the walls of the shell a steam delivery space surrounding a considerable portion of the tube nest, and extending throughout the entire longitudinal length of the tube nest one or more substantially annular intake manifolds located in the bore of the tube nest for withdrawing air and non-condensable gases radially from the nest, an air and non-condensable gas offtake main extending longitudinally through the hollow interior of the tube nest and connecting with the respective manifolds, and means for passing cooling fluid through the hollow interior of the tube nest and to the tubes, whereby the cooling fluid is utilized to reduce the temperature of the air and non-condensable gases before its entry into the tube nest.

18. In a condenser, the combination of a shell having a steam inlet and a condensate outlet, a substantially hollow cylindrical nest of tubes disposed within the shell and defining with the walls of the shell a steam delivery space surrounding a considerable portion of the tube nest and extending throughout the entire longitudinal length of the tube nest, tube sheets and water boxes fitted at each end of the tube nest and fixedly secured to the shell, tube supporting plates located intermediate of the tube sheets and dividing the shell longitudinally into a plurality of compartments, a substantially annular intake manifold provided for each compartment and located in the bore of the tube nest for withdrawing air and non-condensable gases radially from the tube nest, an air and non-condensable gas offtake main extending longitudinally through the hollow interior of the tube nest and connecting with the respective intake manifolds, and means for conveying cooling water through the hollow interior of the nest and to the tubes of the nest, whereby the air and non-condensable gases passing through the hollow interior of the tube nest are effectively cooled before their removal from the condenser.

19. In a condenser, the combination of a shell having a steam inlet and a condensate outlet, a substantially hollow cylindrical nest of tubes disposed within the shell and defining with the walls of the shell a steam delivery space surrounding a considerable portion of the tube nest and extending throughout the entire longitudinal length of the tube nest, a conduit occupying the bore of the tube nest, an annular tube sheet associated with each end of the tube nest, a water box associated with each tube sheet, one of said water boxes being arranged to convey cooling water to the conduit and to discharge cooling water from the tube nest and the other of said water boxes being arranged to convey cooling water from the conduit to the tube nest, and an air and non-condensable gas offtake main extending longitudinally through the interior of the conduit, said offtake main having its entrant portions communicating with the inner periphery of the tube nest and having its discharge portion terminating in a wall of one of the water boxes.

20. In a condenser, the combination of a shell having a steam inlet and a condensate outlet, a substantially hollow cylindrical nest of tubes disposed within the shell and defining with the walls of the shell a steam delivery space surrounding a considerable portion of the tube nest and extending throughout the entire longitudinal length of the tube nest, a conduit occupying the bore of the tube nest, an annular tube sheet associated with each end of the conduit, each of said tube sheets having its inner periphery connected to the conduit and its outer periphery connected to the shell, a water box associated with each tube sheet, one of said water boxes having a cooling water inlet passage connecting with the conduit and a cooling water outlet passage connecting with the tube nest and the other of said water boxes being arranged to convey cooling water from the conduit to the tube nest, and an air and non-condensable gas offtake main extending through the interior of the conduit, said offtake main having its entrant portions communicating with the inner periphery of the tube nest and having its discharge portion terminating in a wall of one of the water boxes.

21. In a condenser, the combination of a shell having a steam inlet and a condensate outlet, a substantially hollow cylindrical nest of tubes disposed within the shell and defining with the walls of the shell a steam delivery space surrounding a considerable portion of the tube nest and extending throughout the entire longitudinal length of the tube nest, a conduit occupying the bore of the tube nest, an annular tube sheet associated with each end of the conduit, each of said tube sheets having its inner periphery connected to the conduit and its outer periphery connected to the shell, a water box associated with each

tube sheet, one of said water boxes having a cooling water inlet passage connecting with the conduit and a cooling water outlet passage connecting with the tube nest and the other of said water boxes being arranged to convey cooling water from the conduit to the tube nest, annular tube supporting plates located intermediate of the tube sheets and dividing the space intervening between the conduit and the shell into a plurality of compartments, an annular intake manifold for each compartment located in the bore of the tube nest for withdrawing air and non-condensable gases radially from the nest, and an air and non-condensable gas offtake main located in the conduit and connecting with the respective manifolds.

In testimony whereof, I have hereunto subscribed my name this second day of February, 1927.

DAVID W. R. MORGAN.
